United States Patent Office.

GEORGE W. BROWNE, OF BROOKLYN, NEW YORK.

Letters Patent No. 74,296, dated February 11, 1868.

IMPROVEMENT IN ROW-LOCKS.

The Schedule referred to in these Letters Patent and making part of the same.

TO ALL WHOM IT MAY CONCERN:

Be it known that I, GEORGE W. BROWNE, of the city of Brooklyn, in the county of Kings, and State of New York, have invented a new and useful Improvement in "Row-Locks;" and I do hereby declare that the following is a full, clear, and exact description of the construction and operation of the same, reference being had to the annexed drawings, making a part of this specification, in which—

Figure 1 is a vertical cross-section,

Figure 2 a side elevation,

Figure 3 a plan and section of the "lock base-plate," and

Figure 4 a plan and section of the "eccentric"—

Similar letters of reference indicating corresponding parts.

The nature of my invention relates more particularly to an improvement in a "row-lock," for which I hold Letters Patent of the United States, bearing date April 30, 1867, and numbered 64,280, and having in view a more reliable attachment between the gunwale of the boat and the row-lock than is obtained by the form manufactured under the patent mentioned above, in which I stated that the weight and action of the oars would be sufficient to adjust and hold the row-lock in its proper position on the upper edge of the gunwale of the boat. Extensive experiment and daily use since that time have demonstrated that while the foregoing claim was, in the main, correct, nevertheless, at the two extreme points of the stroke or sweep of the oars, the angularity of their action, and the decrease of the direct weight consequent thereon, tended to draw the row-lock inboard, thereby unshipping the oars at the end of each stroke. The object of my present invention is to prevent this action, and I will proceed to describe the construction and operation of the arrangement, which I have found to answer every requirement, thereby enabling others skilled in the art to make and use my invention, as herein set forth.

A represents the thole-pin, centrally pivoted and swivelling in the boss-plate B, and passing through and retained in its place by the collar on the eccentric, D, to which it is permanently secured by the transverse-pin *a*. The boss-plate B, with the attached thole-pin, is connected to the "lock base-plate" C by a hinge and pin, E, thereby enabling the plate B and thole-pin A to be wholly removed from the boat, or, when required, to fall inboard, as shown by the red lines in fig. 1. This falling inboard, however, cannot take place unless the thole-pin A, with the attached eccentric, D, is brought into a position at right angles with the gunwale, or, in other words, is made to describe a quadrant in the boss on the plate B, thereby removing the end of the eccentric, D, from under the outer edge of the plate C, as shown more particularly at C' D', fig. 1. When this position is attained, the thole-pin and eccentric easily pass through the opening *b* in the "lock base-plate" C, as shown in fig. 3. The "lock base-plate" C is mortised into and secured to the gunwale by bolts or screws, as shown at X, figs. 2 and 3.

Inasmuch as the eccentric, D, is rigidly secured to the thole-pin A, it will be readily seen that it will follow the thole-pin A throughout that portion of a revolution which the sweep of the oars describe, while at the same time the end, D', will remain under the outer edge of the plate C, as seen at C', thereby preventing the tendency of the thole-pin and plate B to fall inboard, as previously described; and this result will obtain until the thole-pin is brought into the position at right angles with the gunwale, as heretofore set forth, when the whole arrangement will fall inboard, the eccentric, D, passing readily through the opening *b* in the "lock base-plate" C, as herein described.

What I claim as my invention, and desire to secure by Letters Patent, is—

The plate C and eccentric, D, when combined and operated in the manner and for the purpose described.

GEO. W. BROWNE,
